UNITED STATES PATENT OFFICE.

WILLIAM C. PICKELL, OF HIGHLAND PARK, MICHIGAN.

WRAPPING-SHEET HOLDER AND LIQUID-APPLYING DEVICE.

Application filed February 16, 1923. Serial No. 619,483.

To all whom it may concern:

Be it known that I, WILLIAM C. PICKELL, a citizen of United States, residing at 60 Geneva Ave., Highland Park, in the county 5 of Wayne and State of Michigan, have invented a new and useful Wrapping-Sheet Holder and Liquid-Applying Device, of which the following is a specification.

My invention relates to improvements in 10 wrapping sheet holders and moisteners in which a ream or more of gummed paper sheets can be placed diagonally in front of the operator, who can moisten two corners of each sheet, then fold or roll one corner 15 at a time and fasten the moistened corners to the body of the parcel.

One object of my invention is to provide 20 a combined holder and moistener which assists in quick and secure wrapping of all parcels from one position without the use of string.

Another object of my invention is to provide a combined holder and moistener which holds a large number of sheets always in a 25 straight and even alinement, said sheets being always ready to moisten and wrap or fold one after another from the same position.

I attain these and other objects of my in- 30 vention which are illustrated in the accompanying drawing, in which,—

Figure 1—is a side view of the entire moistener shown fastened to one corner of the holder with moistening-pad folded be- 35 tween the moistening rollers. The dotted outlines of the moistening pad shows the different positions it can be held in when the holder is full and when said holder is near- ly empty.

Figure 2—is a front elevation of the moistener showing the opening through which the moistening pad is pulled and the hinges on which it swings.

Figure 3—is a vertical section cut through 45 II—II showing the liquid, the belts or pads, the drum and the rollers, also the cable which helps to pull the moistening pad back into position over the rollers.

Figure 4—is a front elevation of the 50 cover with all the movable parts connected to it.

Figure 5—is a side elevation of the cover and movable parts.

Figure 6—is a front elevation of the drum 55 showing a part in full outline and a part

in section, said sectional part showing the axle and housing containing the spring.

Figure 7—is a plan view of the entire holder and the two moisteners, also a ream of paper upon which is shown a parcel part- 60 ly wrapped.

Figure 8—is a side elevation of the holder, the two moisteners, and a ream of paper. In this view is shown how the operator pulls out the moistening pad and rolls 65 or rubs it over the gummed spots.

Figure 9—is a plan view of a round parcel wrapped and the corner D gummed fast.

Figure 10—is a plan view of a square par- 70 cel wrapped and gummed. Both C and D corners are gummed fast.

Figure 11—is a plan view of a sheet of 75 wrapping paper showing the two gummed corners at C and D.

Similar numerals refer to similar parts throughout the several views.

The support or base 1 is a platform structure and holds the stack of wrapping sheets 2 which are held in place by the guide pins 3—4—5—6—7—8, said guide pins are held in place by bolts 9 which are made to move in slots 10 thus allowing for oversize and undersized sheets. Base 1 has two projecting corners 11—12 which support the two moisteners and these are fastened to base 1 by screws 13. The gummed corners C—D are moistened by the operator who pulls the moistening pad 14 out and rubs it over the gummed corners as shown in Fig. 8 at 15, 80 then corner A is folded over or rolled around the article to be wrapped after which corner B is folded over, then corner C is folded over corner B and gummed fast. The parcel is then rolled and corner D is gummed 85 fast to the body of the parcel as shown at 16 in Fig. 9.

In Fig. 1 the base 17 of the moistener is fastened to the base 1 of the holder by screws 18—18 and said base 17 supports the liquid 100 tank 19 within which is poured the liquid 20 and through which passes the absorbing belt 21.

The drum 22 is made to revolve by pulling the moistening pad out from between the belt 21 and rollers 23. The wire cables 24 are fastened to the moistener pad by the hinge pin 25. From the hinge pin 25 the cables 24 pass over roller 26 and then around the drum 22 in the grooves 27 and 28, the 110

ends of cables 24 are fastened to the drum 22 and when the moistener pad is pulled they unwind from the drum and at the same time cause the drum to revolve and carry the belt 21 through the liquid 20 and over the rollers 29—29.

The spring 30 is fastened to the shaft 31 at 32 and the other end is fastened to the drum hub 33 at 34 which causes the drum 22 to revolve backward and rewind the cables 24—24 around the drum 22 in the grooves 27 and 28. The other ends of the cables 24 are secured at even lengths to each end of the hinge pin 25 and made to draw 15 through grooves at each end of roller 26.

The moistener pad is composed of a frame 35 which also acts as a handle, and three rollers 36 around which revolves the absorbing belt 37 which collects the liquid from belt 21 and carries it to the gummed spots. To the rear end of the moistener pad are fastened one end of the hinge plates 38, the other ends of said hinge plates 38 are fastened to the cover or roll holder 39 by the pin 40 which also supports the guide roller 26. The upper portion of the locating flange 41 is fastened to the lower part of cover 39 and the lower portion supports the drum 22 and fits closely inside of the top of tank 19. 30 At the ends of the rollers 36 are the guide rollers 42 which are flanged to fit the grooves 43 in cover 39 and guide the moistening pad in and out of said grooves. Spring 44 acts as a stop for hinge plates 38 and also pulls them back in place when the tension is released.

Having described my improvement, what I claim as new and desire to secure by Letters Patent is:

40 1. In a wrapping sheet holder and liquid applying device, the combination of a rectangular base support having six vertical pins or posts, adapted to slide in slots diagonally across corners of said base support said posts having screws inserted at the bottom for clamping said posts where they will hold in place a stack of wrapping sheets and allow the operator to fold one at a time until said stack is exhausted, a projecting ledge at each of two adjacent corners, means adapted to support two moisteners upon said ledges.

55 2. The combination with a rectangular base support 1 adapted to hold a stack of wrapping sheets 2, six adjustable posts 3—4—5—6—7—8 held in place by screws 9 which fit in slots 10 of said base support and assist in holding said stack of wrapping sheets together, ledges 11 and 12 on two adjacent corners, two moisteners of like formation fastened to said ledges one moistener at the top corner and one moistener at the left hand corner of said base-support.

60 3. In a wrapping sheet holder and liquid applying device, the combination of a rec-

tangular base support having ledges at two adjacent corners, with two moisteners alike in formation and placed on said ledges, said moisteners having hinged moistening pads 14 so mounted that they may swing out and down and across the two adjacent corners of a wrapping sheet lying upon said base support.

4. In a wrapping sheet holder and liquid applying device, the combination of a rectangular base support having ledges at two adjacent corners, with two moisteners alike in formation and placed on said ledges; said moisteners having a box-shaped housing, said housing being constructed and arranged in three parts, a lower part 19 being provided and adapted to hold a portion of liquid, a middle part 41 supporting a rotary drum adapted to carry an absorbing belt through said liquid and an upper part 39 supporting rollers 29, over which there is provided means for carrying said liquid from the lower part 19 to the upper part 39 through an absorbing belt 21; means for conveying said liquid through absorption into belt 21; also a similar absorbing belt 37 being provided and adapted to press over the top of belt 21 and absorb said liquid from said belt 21, and means for conveying said liquid to a gummed spot on a sheet of paper 95 lying on said base-supports.

5. In a wrapping sheet holder and liquid applying device, the combination of a flat rectangular base-support having ledges at two adjacent corners, with two moisteners alike in formation placed on said ledges, said moisteners having a housing of three parts joined together in one box-shaped aperture, a lower part 19 being constructed and arranged with a cavity for holding liquid and also means for supporting the middle and upper parts 41—39, the middle part 41 being constructed and arranged to fit partly within the lower part 19 and partly within the upper part 39, said middle part being provided with a rotary drum 22 said rotary drum being adapted to rotate through said liquid and a belt 21 which will absorb and be saturated with said liquid, transferring it over the top, where rollers 29 and a moistening pad 37 are provided to collect and carry said liquid to a gummed spot on a sheet of paper lying on said base-support.

6. In a wrapping sheet holder and liquid applying device, the combination of a rectangular base-support having ledges at two adjacent corners, with two moisteners alike in formation and placed on said ledges, said moisteners each being constructed with a box-shaped housing of three parts, a rotary drum 22 being provided within said housing having a coil spring around its axle, an absorbing belt 21 so constructed as to rotate through liquid lying within the lower part of said housing by means of two cables 130

which are constructed to wrap and unwrap around said drum said drum containing two grooves, each groove being deep enough to provide for three or more coils of said cable.

- 5 7. In a wrapping sheet holder and liquid applying device, the combination of a rectangular base support having ledges at two adjacent corners, with two moisteners alike in formation, each of said moisteners having moistening pads constructed and arranged with a set of revolvable rollers 36 being in a horizontal row and having around them an endless absorbing belt said rollers being supported by a frame and handle so 10 arranged as to slide over the top portion of the cover part of the moistener housing, said frame or handle of said moistening pads being also provided with swinging arms, means for holding said pads in true alignment with the housing and rollers, and causing said pads to swing back in the same place each time they are swung out to moisten a gummed spot on the wrapping sheets lying on said base supports.
- 15 8. In a wrapping sheet holder and liquid applying device, the combination of a rectangular base support having ledges at two adjacent corners, with two liquid moisteners alike in formation placed on said ledges, said 20 moisteners having the moistening pads 14, the frame and handle 35 of moistening pads, the cables 24 fastened to the rear ends of said frame, the other ends of said cables being securely fastened and wrapped around 25 each end of the drum 22, and a spring around the axle of said drum adapted to hold the drum in one position until after the moistening pads are pulled out and down and over the gummed corners of wrapping 30 sheets lying upon said base supports.
- 35 9. In a wrapping sheet holder and liquid applying device the combination of a rectangular base-support having ledges at two adjacent corners, with two moisteners alike in formation placed on said ledges, said 40 moisteners having cables 24 fastened to and wound in grooves around drums 22 which are constructed and which are designed to rotate within each moistener, said drums each having an axle 31 around which is arranged an axle housing 33, a spring being placed around said axle and fastened to one end thereof, the other end of said spring being fastened to said axle housing, and means for winding and unwinding said cables 45 around said drums when the moistening pads 14 are being pulled out of their respective places and down across the gummed corners of wrapping sheets lying upon said base-supports.
- 50 10. In a wrapping sheet holder and liquid applying device, the combination of a rectangular base support having ledges at two adjacent corners, with two liquid moisteners alike in formation placed on said ledges, said moisteners having moistening pads 14 on the rear ends of which are fastened two cables 24, said cables having sufficient length to wind around drums 22 and allow said pads 14 to be 55 pulled out far enough to moisten gummed corners of wrapping sheets lying upon said base supports.
- 60 11. In a wrapping sheet holder and liquid applying device the combination of a rectangular base support having ledges at two adjacent corners, with two moisteners alike in formation placed on said ledges, said moisteners having cables 24 which wind around the outer surface in grooves, of the 65 drums 22, said drums 22 each having an axle 31 around which is a housing 33 and a spring 30, one end of the spring being fastened to the housing and the other end to the axle, and means for winding and unwinding said cables around said drums when the operators pull moisteners 14 out of the housings and down across the gummed corners of wrapping sheets lying upon said 70 base supports.
- 75 In testimony whereof I affix my signature.
WILLIAM C. PICKELL.
